FIG. 1

FIG. 2

FIG. 1 is a side elevational view of the starboard side of a sailboat. The port side is substantially identical in appearance to the starboard side.

FIG. 2 is a top plan view of the sailboat.

FIG. 3 is an elevational view from the bow.

FIG. 4 is an elevational view from the stern.

FIG. 5 is a composite of hull half sections taken at the respective stations of FIG. 1 in accordance with conventional practice.

FIGS. 2, 3 and 4 are shown with the mast, boom, sails, standing and running rigging omitted for convenience of illustration.

The partial disclosure of surface texture of FIG. 2 is representative of the complete appearance within the borders shown.

FIG. 3

FIG. 4

What is claimed is:

The ornamental design for a sailboat, substantially as shown and described.
